UNITED STATES PATENT OFFICE.

CHARLES F. SCHROEDER AND AUGUST A. QUEDENSLEY, OF CHICAGO, ILLINOIS.

HAMMER.

Original application filed January 19, 1922, Serial No. 530,471. Divided and this application filed October 25, 1922. Serial No. 596,727.

To all whom it may concern:

Be it known that we, CHARLES F. SCHROEDER and AUGUST A. QUEDENSLEY, both citizens of the United States, and residents 5 of Chicago, in the county of Cook and State of Illinois, have invented certain new and useful Improvements in Hammers, of which the following is a specification.

Our invention relates to hammers of that 10 type in which the hammer body of hard metal such as cast iron or steel is constructed to be adapted to receive and clamp faces of softer metal, and this application may be considered as a divisional application arising 15 out of original application Serial No. 530,471 filed January 19, 1922, in which original application the hammer herein claimed is shown but cannot be specifically claimed.

20 The construction of our improved hammer is clearly shown on the accompanying drawing, in which—

Fig. 1 is a side elevational view of the hammer head partly broken away,

25 Fig. 2 is an inner side elevational view of the head with parts broken away,

Fig. 3 is a vertical diametral section on plane 3—3, Fig. 2 of the head showing the parts separated ready for assembly, and

30 Fig. 4 is a sectional view on plane 4—4, Fig. 2.

The hammer head is constructed of the two body parts A and B each in the form 35 of an integral casting of cast iron, steel or any other suitable metal. The body parts or halves are each of semi-circular cross section throughout and when brought together form the head body of circular cross section throughout but tapering towards the ends.

40 The part A has the tapered boss 10 extending at right angles from the middle thereof, and the part B has the tapered hole 11 for snugly receiving the boss when the parts are brought together. Through the part A and 45 the boss 10 extends the hole 12 for receiving the hammer handle *h*, the handle being securely held in the part A by means of a wedge 13. One of the parts, as for example the part A, has screw holes 14 and 15 for receiving screws 16 and 17 which thread into the openings 18 and 19 provided in the

part B, the screws serving to securely hold the parts together with the tapered boss fitting snugly in the tapered hole, thereby making the hammer the same as a solid 55 hammer and relieving all strain on the screw.

The part A has the semi-circular dovetail pockets 20 and 21 in its ends and the part B has similar pockets 22 and 23 in its ends, the pockets 20, 22 and 21, 23, respectively forming circular dovetail pockets for receiving the hammer faces when the parts A and B are secured together. These pockets receive the dovetail ends 24 of faces 25 which may be of lead, copper, brass, fibre, rawhide or any other desired material, the dovetail ends being securely and tightly held so that the faces seat accurately and tightly against the hammer body when the 70 parts A and B are secured together. By making the body parts in the form of similar halves with substantially the same amount of metal and weight the parts are greatly strengthened and furthermore each presents 75 the same abutment area at its ends to the faces. When the parts are securely drawn together by the screws with the tapered boss fitting accurately and snugly in the tapered hole the parts function together like a solid 80 head to relieve the screws from any blow strain and also to protect the handle. The long boss extending entirely through the part B receives the force of the blows on the part B and distributes it to the part A, in 85 this manner fully protecting the handle, and relieving the screws of all strain except that necessary to keep the parts A and B held together.

Having described our invention, we claim 90 as follows:

In a hammer, the combination of a head and a handle, said head comprising an outer body part and an inner body part, one of 95 said parts having a boss extending therefrom and there being a handle receiving hole through said part and boss, said boss being tapered on the outside, said other part having a hole for receiving the handle and said hole being tapered to snugly fit said boss 100 when the parts are brought together, semi-circular dovetail pockets in the ends of each

part adapted to form circular dovetail pockets when the parts are brought together, and faces having dovetail extensions received in said dovetail pockets when said parts are brought together to be thereby securely locked in said parts, said parts except for said holes and said boss and said pockets being of semi-circular cross sec-

tion throughout whereby to form the head of circular cross section. ¹⁰

In witness whereof, we hereunto subscribe our names this 19th day of October, A. D. 1922.

CHARLES F. SCHROEDER.
AUGUST A. QUEDENSLEY.
